EXPANDING HAIR CURLING ROD

Silvere Brancaccio, Washington, D. C.

Application October 7, 1953, Serial No. 384,723

3 Claims. (Cl. 132—42)

This invention relates to a hair curling rod of the extensible type wherein the rod is split longitudinally and provided with means for expanding the rod as hair is wrapped thereon and in which the expanding means is relieved so that the rod contracts with the hair thereon to relieve tension in the hair as hair wound tightly on a rod impedes the penetration of the permanent waving and neutralizing solution, and in particular this invention includes cams positioned in both ends of a longitudinally split hair curling rod in which both cams are mounted on the same shaft and are adapted to be operated by knobs on the ends of the shaft.

The purpose of this invention is to provide an improved hair curling rod wherein both ends of the rod are spread and contracted simultaneously and wherein the spreading and contracting means is adapted to be actuated from either end of the rod.

This invention is an improvement over the cold permanent wave rod of my co-pending application filed April 6, 1953 with the Serial No. 347,060 in that whereas the rod of the co-pending application is spread with one cam at the center, the rod of this application is spread with cams at both of the ends and the cams are mounted to spread both ends simultaneously.

The object of this invention is, therefore, to provide a longitudinally split hair curling rod in which spreading means are provided in both ends of the rod and in which the spreading means in the ends of the rod are adapted to be actuated simultaneously by a knob at one of the ends of the rod.

Another object of the invention is to provide a longitudinally split hair curling rod that is adapted to be actuated with either a rotating or sliding action of spreading means within the rod.

A further object of the invention is to provide an improved longitudinally split hair curling rod having expanding means therein in which the rod is of a simple and economical construction.

With these and other objects and advantages in view the invention embodies a hair curling rod formed with two semi-circular sections, with resilient means for holding the sections together and with spreading means extended through the rod and adapted to be actuated by a longitudinally disposed shaft extended through the rod.

Other features and advantages of the invention will appear from the following description taken in connection with drawings, wherein:

Figure 1 is a perspective view illustrating the improved hair curling rod showing the rod with the parts expanded.

Figure 2 is a side elevational view of the rod also showing the rod with the parts expanded and also showing the knobs on the ends of the shaft extended through the rod in the position in which the rod is contracted in dotted lines.

Figure 3 is a longitudinal section through the rod with the parts in the position shown in Fig. 2 and also with the parts on an enlarged scale.

Figure 4 is a cross section through the rod taken on

2

line 4—4 of Fig. 3, showing the parts on a still further enlarged scale and also showing the parts in expanded positions.

Figure 5 is a section similar to that shown in Fig. 4 with the parts shown in contracted positions.

Figure 6 is a cross section through the intermediate portion of the rod with the elastic strap extended from end to end of the rod omitted.

Figure 7 is a side elevational view of the rod with the parts as shown in Fig. 2 and illustrating a modification wherein the cam actuating instrumentalities are rotated instead of being moved longitudinally.

Figure 8 is a longitudinal section through the rod shown in Fig. 7, the parts being shown on an enlarged scale.

Figure 9 is a cross section through the rod shown in Figs. 7 and 8, taken on line 9—9 of Fig. 8 showing the parts on an enlarged scale, and showing a rod in the contracted position.

Figure 10 is a similar section showing the rod expanded.

Figure 11 is a section taken on line 11—11 of Fig. 8 illustrating the bearing for the shaft at one end of the rod and also showing the parts on an enlarged scale.

Figure 12 is a longitudinal section through one end of the rod illustrating a modification wherein a combination sliding and rotating cam is provided, showing the parts in the contracted positions.

Figure 13 is a longitudinal section similar to that shown in Fig. 12 showing the parts in the expanded positions and wherein the parts are expanded by a longitudinal movement of the cams.

Figure 14 is a perspective view illustrating the cams used in Figs. 12 and 13 with the cams mounted on a shaft having knobs on the ends thereof.

Figure 15 is a cross section through the rod shown in Figs. 12 and 13 being taken on line 15—15 of Fig. 12 and showing the parts on an enlarged scale.

Figure 16 is a similar view showing the parts expanded.

Referring now to the drawings wherein like reference characters denote corresponding parts the improved hair curling rod of this invention includes a section 10, substantially semi-circular in cross section, a section 11, similar to the section 10, a shaft 12 extended longitudinally through the rod and having cams 13 and 14 thereon and elastic bands 15 and 16 for resiliently urging the sections 10 and 11 against the cams 13 and 14, respectively. The shaft 12 is provided with a head 17 on one end and a knob 18 having slots 19 therethrough on the other and with the shaft in the position shown in Fig. 3 the cams 13 and 14 are in engagement with cam surfaces 20 and 21 on the inner surface of the section 10 and 22 and 23 on the inner surface of the section 11.

The semi-circular sections 10 and 11 are provided with enlarged ends and the intermediate portions are formed with concave surfaces providing a rod with a comparatively small central portion.

As shown in Figures 2 and 3 one end of the section 10 is provided with a plate 24 having a slot 25 therein and the end of the shaft 12 on which the head 17 is positioned, and which extends through the slot, is provided with a shoulder 26 which abuts the outer surface of the plate 24. A pin 27 which forms the end of the shaft 12 extends from the shoulder 26, providing means for holding an eye 28 of a strap 29, preferably of elastic material.

The strap 29 is mounted on the opposite end of the rod with an eye 30 that is positioned in a groove 31 formed by a disc 32 on the end of the section 11.

The knob 18, which is positioned on the end of the shaft opposite to that on which the head is carried, extends through a slot 33 in the disc 32, and the outer surface of the knob is provided with a split stem 34 having a ridge 35 on the outer end. The stem 34 is adapted

to receive the eye 30 of the strap 29 whereby the strap may be, selectively, mounted in the groove 31 or on the stem 34 of the shaft as may be desired.

The bands 15 and 16 which are of elastic or spring material are positioned in semi-circular slots in the sections, the section 10 having semi-circular grooves 36 and 37 for receiving portions of the band therein and the section 11 having complementary semi-circular grooves 38 and 39 therein.

The section 10 is provided with perforations 40 and 10 similar perforations are provided in the section 11, as indicated by the numeral 41. The perforations allow the lotion to pass through the rod to make a faster process. The outer surface of the section 10 is also provided with serrations or teeth 42 which facilitate gripping the ends of hair on the outer surface of the rod in starting a curl.

The inner portion of the section 10 is provided with recesses 43 and 44 that are positioned to receive the cams 13 and 14 and similar recesses 45 and 46 are provided in the section 11 whereby with the cams moved longitudinally into the recesses the sections are moved together by the elastic bands.

In starting a curl on the rod illustrated in Figs. 1 to 6 inclusive the eye 34 of the strap 28 is removed from the head on the end of the shaft 12 and the shaft is moved to the position shown in Fig. 4 by knob 18 whereby the cams 13 and 14 separate the sections 10 and 11 to expand the rod. With the rod in the expanded position ends 25 of hair for a curl are held against the teeth 42 and the rod is rotated toward the head with the hair being wrapped tightly thereon. Upon engagement of the rod with the head the eye 34 of the strap 28 is snapped over the end of the rod and by pressing inwardly on the knob 18 sections of the rod are contracted, thereby relieving the tension of the hair wrapped on the rod.

In the design illustrated in Figs. 7 to 11, inclusive, the rod is formed with sections 50 and 51, substantially semi-circular in cross section with an end wall 52 extended from the section 50 over the end of the section 51 and 40 with an end wall 53 extending from the section 51 over the end of the section 50 and the sections are resiliently held together with elastic bands 54 and 55.

In this design the sections are expanded by cams 56 and 57 on a shaft 58 and with the shaft rotated by knobs 59 and 60 positioned on the ends thereof. With the cams formed as illustrated in Figs. 9 and 10 the cams coat with cam surfaces 61 in the sections 50 and 62 in the section 51 and as the cams are moved from the positions shown in Fig. 9 to the positions shown in Fig. 10 the 45 sections of the rod are expanded.

The shaft 58 extends through an opening 63 in the plate 52 and also through an opening 64 in the plate 53 and, as illustrated in Fig. 8 the elastic bands are positioned in semi-circular grooves 65 and 66 in the section 50 and 67 and 68 in the section 51. The section 50 is also provided with teeth 69, similar to the teeth 42.

In this design hair is retained on the rod with a cord or strap 70, one end of which is positioned in a recess 71 at the end of an opening 72 in the knob 60 and the other adapted to be extended through slots 73 and 74 in the knob 59. The cord or strap 70 is provided with an enlarged end 75 by which the cord may be gripped by a thumb and forefinger so that it may be stretched and inserted in the slots 73 and 74.

In the design illustrated in Figs. 12 to 16, inclusive the rod is formed with sections 76 and 77 and the sections, which are resiliently held with elastic bands 78 and 79 are expanded by cams 80 and 81 on a shaft 82, the ends of the shaft being provided with knobs 83 and 84.

With the cams formed as illustrated in Figs. 14, 15, and 16 the sections of the rod may be expanded by either rotating the shaft or by sliding the shaft longitudinally in the rod.

The section 76 is formed with recesses 85 and 86 that 75

are positioned to receive the cams 80 and 81 and corresponding recesses 87 and 88 are provided in the section 77. With the cams positioned in the recesses the sections are spread by rotating the shaft and when the shaft is moved longitudinally the cams 80 and 81 engage cam surfaces 89 and 90 in the section 76 and 91 and 92 in the section 77, to spread the rod.

Also in this design the section 76 is provided with a head 93 having an annular groove 94 therein and the section 77 is provided with a similar head 95 having an annular groove 96 therein. The shaft 82 extends through a slot 97 in the head 93 and also through a slot 98 in the head 95. The outer surfaces of the knobs 83 and 84 are provided with slots 99 and 100, respectively through which the ends of the elastic strap or cord may be placed for securing hair on the rod.

With the improved expanding hair curling rod of this invention formed in either of the designs shown the rod is applied to groups of strands of hair, preferably with the hair slightly wet and with the ends of the strands of hair placed on the teeth of one section of the rod, the rod is rolled toward the scalp binding the hair tightly thereon with the rod in the open or expanded position. Upon reaching a position against the scalp a strap, cord, or other means secured to a knob or head at one end of the rod is extended over the hair on the rod with the opposite end secured in a knob or head on the opposite end of the rod. With the hair secured on the rod in this manner the cams are actuated to release the sections whereby the elastic bands or springs contract the rod relieving tension in the hair.

With the tension relieved in the hair on the rod the lotion is applied to the hair and as the hair is not tight the lotion penetrates the areas between and around the strands of hair thereby coming in contact with substantially all strands and consequently activating the process.

Although this expanding hair curling rod is particularly adapted for professional use in beauty shops it is also adapted for individual use in doing a home permanent. This improved curling rod is also particularly adapted for hair curling and for cold permanent hair waving.

It will be understood that although the sections forming the body of the curler or hair curling rod are shown comparatively solid the walls of the sections may be made of different material such as sheet metal, wood, plastic, die-castings or the like.

This improved hair curling rod is of the type especially adapted to be used for more efficiently and effectively curling the hair, to provide better and softer curls and reducing the dryness of the hair.

It will also be understood that other modifications, within the scope of the appended claims, may be made in the design and arrangement of the parts without departing from the spirit of the invention.

What is claimed is:

1. In an expanding hair curling rod, the combination which comprises a pair of complementary semi-circular sections positioned to provide a substantially cylindrical rod with an annular concave surface in the intermediate part and with enlarged ends, each of said enlarged ends being provided with an annular recess spaced inwardly from the end and also with a semi-circular flange, the flanges extending from one section and at least partially overlapping the end surface of the other section, the intermediate portion of one section also having serrations projecting from the surface thereof, rubber bands extended around the complementary sections and positioned in the annular recesses, the inner surfaces of the enlarged ends of the sections having cam surfaces therein, a rod extended between said sections and positioned longitudinally of the hair curling rod, said rod extended through the hair curling rod having heads on both ends and cams integral therewith, the cams being positioned to register with the cam surfaces in the enlarged end sections of the complementary sections, and said cams being shaped whereby

upon rotation of the rods by one of the heads the cams spread the complementary sections, one of said heads having a recess therein and the other crossed slots in the outer surface, and an elastic strap positioned with one end secured in a recess of the head at one end of the rod and the other adapted to be retained in one of the slots extended through the head at the opposite end of the rod.

2. In an expanding hair curling rod, the combination which comprises a pair of complementary semi-circular sections positioned to provide a substantially cylindrical rod with an annular concave surface in the intermediate part and with enlarged ends, each of said enlarged ends being provided with an annular recess spaced inwardly from the end and also with a semi-circular flange, the flange extending from one section and at least partially overlapping the end surface of the other section, the intermediate portion of one section also having serrations projecting from the surface thereof, elastic rubber bands extended around the complementary sections and positioned in the annular recesses, the inner surfaces of the enlarged ends of the sections having cam surfaces therein, a shaft extended between said sections and positioned longitudinally of the hair curling rod, said shaft extended into the hair curling rod having a head on at least one end and cams integral therewith, the cams being adapted to cooperate with the adjacent cam surfaces in the complementary sections whereby upon actuation of said shaft the cams spread the complementary sections, and an elastic strap adapted to cooperate with said complementary sections, with one end of the elastic strap positioned and secured at one end of the hair curling rod and adapted to be extended and secured to the other end of the curling rod, the elastic strap being positioned and adapted to cooperate with the complementary sections of the hair curling rod for holding and securing against unwinding a tress of hair wound thereon; the shaft having a head on at least one end being adapted to cooperate with the adjacent cam surfaces in the complementary sections of the

10

20

25

30

35

hair curling rod whereby upon rotation the complementary sections of the hair curling rod contract to release the tension of the tress of hair wound thereon.

3. In an expanding hair curling rod, the combination which comprises a pair of complementary semi-circular sections positioned to provide a substantially cylindrical rod with an annular concave surface in the intermediate part and with enlarged ends, each of said enlarged ends being provided with a semi-circular flange, the flange extending from one section and at least partially overlapping the end surface of the other section, elastic elements extended around the complementary sections and spaced inwardly from the ends thereof, the inner surfaces of the enlarged ends of the sections having cam surfaces therein, a shaft extended longitudinally between said sections, positioned on the axis of the hair curling rod and having spaced cams thereon, said cams being positioned to coact with the cam surfaces of the enlarged ends of the sections of the hair curling rod, the said cams being shaped whereby upon actuation of the shaft the cams engage the cam surfaces, spreading the complementary sections, and an elastic strap positioned with one end secured at one end of the hair curling rod and with the other adapted to be engaged with the shaft extended between said sections.
